US00D946995S

(12) **United States Design Patent** (10) Patent No.: **US D946,995 S**
(45) Date of Patent: ** *Mar. 29, 2022

(54) **MULTI-TOOL WITH BIT SLOT**

- (71) Applicant: **THE SHERWIN-WILLIAMS COMPANY**, Cleveland, OH (US)
- (72) Inventors: **Victor J. Levand**, Lyndhurst, OH (US); **Sharad Gaurav**, Cleveland, OH (US); **Sarah Bridget Mulroy**, Rocky River, OH (US); **Joshua R. Robertson**, North Ridgeville, OH (US); **Edward Ray Goodwin**, Westlake, OH (US); **Randi Boss**, Avon Lake, OH (US); **Michael C. Lambertson, Jr.**, Aurora, OH (US)
- (73) Assignee: **The Sherwin-Williams Company**, Cleveland, OH (US)
- (*) Notice: This patent is subject to a terminal disclaimer.
- (**) Term: **15 Years**
- (21) Appl. No.: **29/772,850**
- (22) Filed: **Mar. 4, 2021**

CLAIM

The ornamental design for a multi-tool with bit slot, as shown and described.

DESCRIPTION

FIG. 1 is a top front perspective view of an embodiment of a multi-tool with bit slot showing a new design;

FIG. 2 is a top rear perspective view of the multi-tool as illustrated in FIG. 1;

FIG. 3 is a bottom rear perspective view of the multi-tool as illustrated in FIG. 1;

FIG. 4 is a top view of the multi-tool illustrated in FIG. 1; FIG. 5 is a bottom view of the multi-tool illustrated in FIG. 1;

FIG. 6 is a front view of the multi-tool illustrated in FIG. 1; FIG. 7 is a rear view of the multi-tool illustrated in FIG. 1;

FIG. 8 is a left side view of the multi-tool illustrated in FIG. 1; and,

FIG. 9 is a right side view of the multi-tool illustrated in FIG. 1.

The broken lines depict portions of the multi-tool with bit slot in which the design is embodied that are not considered part of the claimed design.

1 Claim, 5 Drawing Sheets
